UNITED STATES PATENT OFFICE.

EDWARD G. ROBERTSON, OF NEWARK, NEW JERSEY.

HARNESS-SADDLE.

SPECIFICATION forming part of Letters Patent No. 423,574, dated March 18, 1890.

Application filed May 10, 1889. Serial No. 310,231. (No model.)

To all whom it may concern:

Be it known that I, EDWARD G. ROBERTSON, a citizen of the United States, residing at Newark, in the county of Essex and State of New Jersey, have invented certain new and useful Improvements in Harness-Saddles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to certain improvements in that class of harness-saddles illustrated or represented by the one shown in my prior patent, No. 393,926, issued from the United States Patent Office on the 24th day of December, 1888.

The object of this invention is to provide a harness-saddle having the feature shown in said prior patent, but adapted for other grades and kinds of harness.

The invention consists in the improved harness-saddle and in the arrangements and combinations of parts, substantially as will be hereinafter set forth, and finally embodied in the clauses of the claim.

Referring to the accompanying drawings, 30 embraced in two sheets, in which like letters indicate corresponding parts in each of the several figures, Figure 1 is a side elevation of the improved saddle. Fig. 2 is a plan of a portion of the same, a certain top leather being removed to show the parts below more clearly. Fig. 3 is a section taken at line x, Fig. 2. Fig. 3^a is a section, enlarged, taken on line y, Fig. 1. Fig. 4 is a plan of a leather top piece, showing a stiffening-plate therein; 40 and Fig. 5 is a section taken on line x', Fig. 4. Fig. 6 illustrates a modified construction of a certain top plate of the saddle, and Fig. 7 is a central vertical section showing said plate in its relation to the bottom plate. Fig. 45 8 is a detail plan of a skirt, showing certain tongues formed at the end thereof.

In said drawings, a indicates a metallic bottom plate, which is deeply concave or hollow on its upper side and convex on its under side in cross-section, as indicated in Fig. 3^a, and in side elevation, as in Fig. 1, is angular

and shaped to conform to the curves of the horse's back. The said bottom plate is cast or formed in an integral piece and presents a pad-like roundness, because of the shape above described, such as is displayed by the ordinary stiffened pads. The said bottom plate, furthermore, is perforated, as indicated in Fig. 3^a, where it engages the back of the animal to lighten the saddle and to provide 60 ventilating-passages, whereby the pad may be kept at a lower temperature.

Within the concavity of the bottom plate, adjacent to the upper edges thereof, is arranged an upper or top plate b of metal. This is also 65 angular when viewed in side elevation, and when arranged in position engages or lies quite close to the upwardly-extending flanges or edges b' b' of the bottom plate, for the purpose of holding a covering leather or lining 70 c in place on said bottom plate and to fill or cover the concavity and provide a bearing for the top leather. The said top plate is held to the bottom plate by screws or other fasteners d d, one or more of which enter an upwardly-projecting stud e, cast on the bottom plate, which stud acts as a center support for the said top plate. The edges of the top plate rest on bearings f, formed at the sides of the flanges b' b', as described in my prior 80 patent. The bottom plate or jockey or tree and the top plate form what may be termed the "frame" of the saddle.

The upper plate differs in its construction from the one previously described in that at 85 its opposite extremities, where the skirt i is fastened to it, said plate is of irregular shape and not uniformly flat, as in my prior device. At the center of said top plate, at the ends thereof, the portion g' is level or flush with the surface of the body portion b'', and at the sides of said portion g' the plate is depressed or bent down to a lower plane, as at g g, to receive the tongues h h of the skirt and bring their upper surfaces flush with the surfaces 95 b''. At j, nearer the extremity of the top plate and between the surfaces g g, the plate is still further bent down, so as to provide a bearing to engage the bottom plate and enable the extremity of the top plate to be secured to the said bottom plate. The surface j being below the surfaces g g allows the

tongue h'' of the skirt to enter and be secured to the portion j , and yet allows ample room for the back-band k to pass beneath the portion g' and be secured thereto by the terret 5 or pad-screw p , as in Fig. 3, or continue its course over the top plate, as in Fig. 7, in the latter case the said top plate being centrally and longitudinally grooved or recessed from one side of the saddle to the other, as at l in 10 Fig. 6, for that purpose. The said groove is of a depth about equal to the thickness of the back-band, so that the latter at its upper face may be approximately flush with the surface b'' , so that the top leather may have a level 15 bearing thereon, as will be understood. The raised portion g' , beneath which the back-band passes, is also level with the portion b'' , so that the top leather or jockey m may lie thereon and be fastened down in place by 20 the terret or a pad-screw.

The skirt may be secured to the top plate by tacks, sewing, or any other suitable fastenings.

By this peculiar arrangement of parts I secure in a saddle of the class referred to peculiar strength and neatness of finish.

To prevent the top leather m from curling at its outer end or ends below the point or points where it is held down by the pad-screws 30 or terret, I have formed the same of a plurality of folds or plies sewed or otherwise united. Between said plies or folds, entirely concealed thereby, is arranged a thin stiffening-plate m' , Figs. 4 and 5. This plate is concaved or cut 35 out at its outer end, where it lies close to the end of the top leather, so that while the corners of the leather are held down by the projecting points of the plate the center will be allowed a limited flexibility over the back-band.

Having thus described my invention, what I claim as new is—

1. The combination, with the concavo convex bottom plate of a saddle, of a top plate arranged therein and provided with a center bearing g' , flush with the body of said top plate, lateral depressions $g\ g$, and central depression j , a skirt having tongues $h\ h\ h''$, and

a back-band held to said bearing g' , substantially as and for the purpose set forth. 50

2. The improved saddle herein described, combining therein a metal bottom plate conforming to the horse's back, as described, a top plate secured to said bottom plate and having at its opposite extremities bearings g' , 55 depressions $g\ g$, and a lower depression j , a skirt having tongues $h\ h\ h''$ secured to said top plate, and a back-band arranged beneath the bearing g' , substantially as and for the purpose set forth. 60

3. In a saddle, the combination, with a metal bottom plate angular to conform to the horse's back and concave on the upper side, forming flanges $b'\ b'$, of a metal top plate resting between said flanges and secured to said bottom plate, said top plate having at the ends thereof a bearing g' , lateral depressions $g\ g$, and a lower central depression j , the said plate being adapted to receive the tongued skirt, substantially as and for the purposes 70 set forth. 65

4. The improved saddle combining, with the angular frame conforming to the horse's back, a top leather consisting of a plurality of folds or plies and a stiffening-plate independent of 75 said frame and interposed between the said plies or folds to prevent the said top leather from turning or curling, substantially as described.

5. The improved saddle combining therein 80 an angular frame, a top leather disposed on the upper side of said frame, and a stiffening-plate having a concaved extremity interposed between the folds of said top leather to prevent the same from curling at the end, and 85 yet allowing a limited flexibility at the center of the extremity of the said top leather, substantially as set forth.

In testimony that I claim the foregoing I have hereunto set my hand this 7th day of 90 May, 1889.

EDWARD G. ROBERTSON.
